Pro Att.

UNITED STATES PATENT OFFICE.

CHARLES C. BLAKE, OF BROOKLINE, MASSACHUSETTS.

ARTICLE-HANDLING MECHANISM.

Original application filed May 18, 1918, Serial No. 235,243. Divided and this application filed October 27, 1921. Serial No. 510,760.

To all whom it may concern:

Be it known that I, CHARLES C. BLAKE, a citizen of the United States, residing at Brookline, in the county of Norfolk and State of Massachusetts, have invented certain new and useful Improvements in Article-Handling Mechanism, of which the following is a specification.

This invention relates to article handling mechanism and more particularly to such mechanism for separating blanks of disk form from a mass and arranging them in serial relation with their curved edges abutting each other.

The object of the invention is to provide an improved mechanism of the character indicated which will be certain in operation and will continually maintain the delivery chute or raceway full of articles ready for separation therefrom and use in any desired connection.

This object is attained by the features and combinations and arrangements of parts hereinafter fully set forth, the advantages of which will be readily understood by those skilled in the art.

The preferred form of the invention is shown in the accompanying drawings which are like a part of the drawings illustrating a machine for making insulated nails which forms the subject matter of my copending application Ser. No. 235,243, filed May 18, 1918, now Patent No. 1,411,951, April 4, 1922, from which the present application is a division.

In the drawings Figure 1 is a plan view of the mechanism; Fig. 2 is a front elevation with a part of the pot broken away to show the interior construction; and Fig. 3 is a central, vertical sectional view.

In the embodiment of the invention illustrated in the drawings the mechanism is particularly constructed for the handling of the wood blocks to be used in the manufacture of insulated nails for securing telephone wires to wood-work, but it will be understood that any disk-like blank may be handled by the mechanism illustrated in the drawings or similar mechanism embodying its principles of construction and operation. With this understanding, in the following description, the articles will be referred to as "blocks" in an inclusive sense.

Referring now to the drawings in which

the various parts are designated by the same reference numerals as are employed in describing the invention of said patent, the blocks, shown in Fig. 2, are introduced into the mechanism initially through a hopper 63 (Fig. 3) formed on a frame 64 which is connected to an annulus or ring 65 by three bolts 66, 67 and 68, (Fig. 2). The ring 65 is connected to a three-armed spider 69 by the bolt 67 and two other bolts 70 and 71 (Fig. 2). The spider 69 is bolted to a bracket 72 (Fig. 1) bolted to a girder or other fixed support 24. When the blocks are thrown into the hopper 63 they fall into a pot 73 bolted to a disk 74 secured to a horizontal shaft 75 journaled in the hopper frame 64 and spider 69. The pot 73 is made in two dish-like sections, each having a flange, which are secured together through the flanges by fastenings comprising distance pieces 76 arranged to leave a central slot 77 between the two sections of such dimensions as to permit the blocks in the pot to slip edgewise therethrough.

The pot 73 is rotated in the direction of the arrow (Figs. 2) and as the pot rotates the blocks fall edgewise into the slot 77 and against the inner surface or wall of the ring 65 along which they roll, by pressure from the pieces 76, until they arrive at an opening 78 in the ring which forms a discharge chute 51, extending, tangentially to the periphery of the pot, through the ring 65. If the chute 51 is empty the blocks roll to the right (Fig. 2) into the chute. If the chute is full, as shown in Fig. 2, the blocks collect in a sector shaped pocket 78^a formed in the ring 65 adjacent the opening 78 and these collected blocks cause the blocks in the slot 77 to roll to the left (Fig. 2) as they reach the end of the chute 51 and drop back into the pot. Attached to the outer end of the chute 51 is a raceway 52 which conveys the blocks to any desired point of discharge. The chute 52 is provided with a central way 79 for the passage of the blocks in serial relation and this way, the chute 51 and the pocket 78^a are enclosed with a cover 80 of transparent material to permit inspection. In order to rotate the pot the shaft 75 is provided with a pulley 84 which receives a belt 85 leading to any convenient source of power.

The scope of the invention having been

indicated and its preferred embodiment specifically described, what is claimed as new, is:—

1. A handling mechanism having, in combination, a stationary ring having an opening therein and a pocket adjacent the opening, a raceway registering with the opening in the ring, and a rotary pot having a slot shaped to permit the articles therein to slip 10 edgewise therethrough and spaced from the ring to cause the articles in the slot to rest on the ring.
2. An article handling mechanism having, in combination, a rotary pot for receiving 15 articles in a mass comprising two dish-shaped sections each having a flange and secured together in spaced relation, a fixed ring surrounding the slot thus produced, and a chute through said ring communicat- 20 ing with said slot.
3. An article handling mechanism having, in combination, a rotary pot for receiving articles in a mass comprising two dish-shaped sections each having a flange and se- 25 cured together in spaced relation, a fixed ring surrounding the slot thus produced, and a chute through said ring arranged tangen- tial to the periphery of the pot and commu- 30 nicating with said slot.
4. An article handling mechanism having, in combination, a rotary pot for receiving articles in a mass comprising two dish-shaped sections each having a flange and se- 35 cured together in spaced relation, a fixed ring surrounding the slot thus produced having a pocket formed in its inner surface op- 40 posite said slot, and a chute leading from said pocket outside the ring.
5. An article handling mechanism having, 45 in combination, a rotary pot for receiving articles in a mass comprising two dish-shaped sections each having a flange and se- cured together in spaced relation, a fixed ring surrounding the slot thus produced, 50 having a pocket formed in its inner surface opposite said slot, and a chute leading from said pocket outside the ring, said pocket and chute being provided with a transpar- ent covering to permit inspection.
6. An article handling mechanism having, 55 in combination, a fixed annulus having a smooth inner surface with a central pocket

at one portion and a discharge chute lead- 60 ing therefrom, and a pot for receiving arti- cles in a mass rotatable within said annulus and constructed to permit articles to rest in a row on said annulus and be swept there- over into said chute or pocket.

7. An article handling mechanism having, 65 in combination, a fixed annulus having a discharge chute therethrough, a rotary pot within said annulus for receiving articles in a mass comprising two sections, and means for securing said sections together including distance pieces forming a central slot which 70 is closed by said annulus except at said dis- charge chute, whereby articles resting in said slot are swept along the annulus to the chute through engagement by said distance pieces.

8. A mechanism for handling disks hav- 75 ing, in combination, a rotary pot for receiv- ing disks in a mass and having a central per- 80 ipheral slot of such dimensions as to per- mit said disks to slip edgewise therethrough, a fixed annulus surrounding the pot for holding the disks in said slot, and a dis- charge chute through the annulus to which 85 the disks in the slot are fed by rotation of said pot.

9. A mechanism for handling disks having 90 in combination, a rotary pot for receiving disks in a mass and having a central periph- 95 eral slot of such dimensions as to permit said disks to slip edgewise therethrough, a fixed annulus surrounding the pot for holding the disks in said slot, a discharge chute through the annulus to which the disks in the slot are fed by rotation of said pot, and a pocket for accumulating the disks and for permit- 100 ting the return of the disks to the mass in the pot when the chute is full.

10. A mechanism for handling disks hav- 95 ing, in combination, a rotary pot for receiv- 100 ing disks in a mass constructed to permit certain of said disks to become aligned in serial relation, means for maintaining said disks aligned, a discharge chute for receiv- ing said aligned disks, and a pocket for causing the return of an excess over the re- quirements of said chute to the mass in the pot.

CHARLES C. BLAKE.
